UNITED STATES PATENT OFFICE.

CARL THEO. OSTERBERG, OF MILWAUKEE, WISCONSIN.

WINDOW SCREEN.

Application filed June 4, 1923. Serial No. 643,205.

The invention relates to frameless window screens, that is, window screens without the usual distending and supporting frame. By reason of the omission of the frame as a fixed part of the screen, the latter, when not in use may be rolled into a small package, compact in form, enabling its convenient handling and storage when not in use in fulfilling its functions.

10 The window screen is so constructed that with the employment of some small adjunctive devices it may be readily secured in position, and as readily removed from position, by very simple operations.

15 Further, the invention embodies devices for exerting a tension upon the screen after the latter has been placed in position in the window, such devices having provisions for adjustment whereby the slack may be easily taken out of the screen, the tension on the screen caused by such adjustment maintaining the screen in its operative position.

20 Another feature residing in the construction of my improved screen is that it is adapted to be placed in position from the inside of the window, thus greatly facilitating its application to all windows irrespective of their altitude above the ground.

25 Other features of my invention will be described in detail, and the novelty thereof will be pointed out in the appended claims.

In the accompanying drawing:—

Figure 1 is a view in elevation looking through a window from the inside, with the sash removed and showing my improved screen as secured in operative position.

Fig. 2 is an enlarged vertical sectional view transversely through the upper part of the screen, showing the manner in which the same is sustained in position.

Fig. 3 is a side view of one of the brackets or guides designed to be attached to the blind stop of the window frame in the location indicated in Figs. 1 and 2, and forming the means for supporting the screen in position.

Referring to the drawing, the numeral 10 indicates a window frame of usual construction, and provided with blind stops 11, one at each side, and a similar horizontal stop 12 at the top of the frame. On the inner face of the vertical stops 11, I attach brackets 13 at opposite points near the top and bottom of the frame, brackets 13 being secured in position by any suitable means.

The screen 14 formed of wire netting is clamped or secured at two opposite ends to upper and lower cross bars 15 and 16. The construction of these bars in a preferred form is shown in Fig. 2, in which the upper bar 15 is constituted of a channel bar 17 and a filler strip 18, about which the end of the wire netting is partially wrapped and retained in position by frictional engagement when the filler strip is wedged into the channel. But other methods of securing the opposite ends of the wire netting to the cross bars may be employed. The length of the wire netting will be such that when it is attached to the crossbars, the whole of the window opening will be covered.

Referring again to the brackets 13 the laterally projecting portions of the same are notched as at 19 for the reception and guidance of the straining rods 20, bent at one end and having a pivotal or other connection with the cross bars 15 and 16. In Fig. 2 the shorter bent end of the straining rods is shown as having a threaded engagement with the bushing 21 seated in the filler strip 18. The longer end of the straining rod 20 is threaded for the reception of a thumb nut 22, adapted to be positioned on the rod and have engagement with one of the lateral extensions of the bracket. When positioned, the straining rod 20 will be guided by the notches 19 in the extensions of the bracket and the alignment of the screen, will be maintained.

In placing the screen the upper cross bar 90 is positioned by placing the same in contact with the outer surface of the blind stops 11 and 12, with the straining rods 20 standing vertically in the notches of the brackets 13, and the thumb nuts 22 supported upon 95 one of the lateral extensions of the brackets. The lower cross bar is similarly placed at the bottom of the window frame, with the lower edge of the bar resting upon the sill. The slack in the wire netting is then taken up by 100 adjusting the thumb nuts 22 on the straining rods. In such adjustment, the tension to which the wire netting is subjected brings the selvages of the same into close engagement with the blind stops 11, so as to complete the closure and enable the screen to 105 fulfill its functions. At the same time, the adjustment brings the inner faces of the cross bars into engagement with the blind stops, and holds the cross bars in the same 110

vertical plane. In removing the screen, the tension of the same may be relaxed by rotating the thumb nuts on the straining rods connected to the cross bar at one end of the screen, but in actual practice it is not necessary to relax the tension in that manner, inasmuch as the straining rods may be pulled out of their engagement with the brackets by means of their pivoted connection with the cross bars.

The purpose of the threaded pivotal connection between the bent ends of the straining rods and the cross bars is also to permit the said straining rods to be unscrewed from the cross bars when it is desired to remove the screen at the end of the season. The screen may then be rolled into a very compact form convenient for handling and storage until again needed. This manner of connecting the shorter bent ends of the straining rods 20 with the cross bars affords also a means for maintaining parallelism of the cross bars with relation to the axis of the straining rods, so that the inner faces crossbars may be brought into a snug engagement with the fixed parts of the window frame and retained in proper position without the use of extraneous devices.

30 The simplicity of construction of my improved screen and the facility with which it may be placed in position and removed, endow it with material advantages. It is obvious that modifications in the arrangement shown may be made without departing from the spirit of my invention. It is also obvious that my improved construction of screen may readily and economically be applied in screening porches, by merely positioning suitable strips in connection with which the screen will be arranged for co-operation in the simple manner before described.

Having thus described my invention, what I claim and desire to secure by Letters Patent of the United States, is:—

1. A detachable window screen comprising a netting and cross bars to which opposite ends of the netting are attached, in combination with a frame, and means for supporting the screen in engagement with the frame, such means comprising notched brackets upon the frame, and straining rods connected to the cross bars and sustained in the notches in the brackets to align the netting with the frame.

2. A detachable window screen comprising a netting and cross bars to which opposite ends of the netting are attached, in combination with a frame, and means for supporting the screen upon the frame, such means comprising notched brackets attached to the frame, and straining rods having a

pivotal connection with the cross bars and guided in the notched brackets to align the netting with the frame.

3. A detachable window screen comprising a netting and cross bars attached to the opposite ends thereof, in combination with means for supporting the screen upon the frame, such means comprising straining rods connected with the cross bars, brackets provided with aligned notches for the reception of the straining rods, and means on the said rods to take up the slack in the netting and maintain the latter in alignment with the frame.

4. A detachable window screen comprising a netting and cross bars attached to the opposite ends thereof, in combination with means for supporting the screen upon the frame, such means comprising straining rods bent at one end for engagement with the cross bars, brackets provided with aligned notches for receiving the straining rods, and means on the latter to take up the slack in the netting and align it with the frame.

5. A detachable window screen comprising a netting and cross bars attached to the opposite ends thereof, in combination with means for supporting the screen upon the frame, such means comprising brackets adapted to be mounted upon the frame, and devices carried by the cross bars for engaging the brackets to hold the cross bars against the frame and maintain the alignment of the netting with the frame.

6. A detachable window screen comprising a netting and cross bars attached to the opposite ends thereof, in combination with means for supporting the screen upon the frame, such means comprising brackets adapted to be mounted upon the frame and adjustable devices connected to the cross bars and removably supported upon the brackets to hold the cross bars against the frame and take up the slack in the netting and align the latter with the frame.

7. A detachable window screen comprising a netting and cross bars attached to the opposite ends thereof, in combination with means for supporting the screen upon the frame, such means comprising straining members pivotally connected to the cross bars and brackets adapted to be mounted upon the frame for engagement with the straining members to hold the cross bars against the frame and the netting in alignment with the frame when the screen is in position.

In testimony whereof, I have signed my name at Milwaukee, this 28th day of May, 1923.

C. THEO. OSTERBERG.
